DESIGN FOR A DISPLAY STAND FOR PHONO- GRAPH RECORD ALBUMS OR THE LIKE

Leonard W. Schneider, New York, N. Y., assignor to Decca Records, Inc., New York, N. Y., a corporation of New York

Application May 23, 1944, Serial No. 113,731

Term of patent 14 years

(Cl. D80—9)

To all whom it may concern:

Be it known that I, Leonard W. Schneider, a citizen of the United States, residing at New York, in the county of New York and State of New York, have invented a new, original, and ornamental Design for a Display Stand for Phonograph Record Albums or the like, of which the following is a specification, reference being had to the accompanying drawing, forming part thereof.

I claim:

The ornamental design for a display stand for phonograph record albums or the like, substantially as shown.

LEONARD W. SCHNEIDER.
